ABSTRACT

This invention relates to 2-(2-methyl-5-nitro-1-imidazolyl)ethyl-2-thiopseudoureas of the formula

wherein R₃ is hydrogen or lower alkyl containing 1-7 carbon atoms and R₁ and R₂ are hydrogen, lower alkyl containing 1-7 carbon atoms, or R₁ and R₂ together are vinylene, nitrovinylene, or trimethylene. The compounds of this invention are prepared by the reaction with 1-(2-chloroethyl)-2-methyl-5-nitroimidazole of thiols or of the pseudothiourea tautomers of thioureas. These compounds are potent anti-protozoal agents.

**2-(2-METHYL-5-NITRO-1-IMIDAZOLYL)
ETHYL-2-THIOPSEUDOUREAS**

This application is a continuation-in-part of our co-pending application Ser. No. 293,069, filed Sept. 28, 1972 now abandoned.

5

The present invention relates to 2-(2-methyl-5-nitro-1-imidazolyl)ethyl-2-thiopseudoureas of the formula

15

15

20

Scheme I

wherein R₃ is hydrogen or lower alkyl containing 1-7 carbon atoms and R₁ and R₂ are hydrogen, lower alkyl containing 1-7 carbon atoms or R₁ and R₂ together are vinylene, nitrovinylene, or trimethylene and pharmaceutically acceptable acid addition salts thereof. Hydrochloric acid, hydrobromic acid, sulphuric acid, phosphoric acid, methane sulphonic acid, ethane sulphonic acid, β -hydroxyethane sulphonic acid, acetic acid, malic acid, tartaric acid, citric acid, lactic acid, succinic acid, fumaric acid, maleic acid, benzoic acid, salicylic acid, phenylacetic acid, mandelic acid, embonic acid, cyclohexylaminosulphonic acid or 1,5-naphthalene disulphonic acid, for example, can be used for salt formation with compounds of the above formula.

A preferred embodiment of R₁ and R₂ together as vinyl and nitrovinyl and R₃ as hydrogen or lower alkyl containing 1-7 carbon atoms and the pharmaceutically acceptable acid addition salts thereof is 1-methyl-2-[2-(2-methyl-5-nitro-1-imidazolyl)ethylthio]-imidazole and the hydrochloride salt thereof.

A preferred embodiment of R₃ as hydrogen or lower alkyl containing 1-7 carbon atoms and R₁ and R₂ together as trimethylene and the pharmaceutically acceptable acid addition salts thereof is 2-[2-(2-methyl-5-nitro-1-imidazolyl)ethylthio]-1,4,5,6-tetrahydropyrimidine and the hydrochloride salt thereof.

A preferred embodiment of R₁, R₂ and R₃ as hydrogen or lower alkyl containing 1-7 carbon atoms and the pharmaceutically acceptable acid addition salt thereof is 1-methyl-2-[2-(2-methyl-5-nitro-1-imidazolyl)ethyl]-2-thiopseudourea and the hydrochloride salt thereof.

The compounds are prepared as shown in Scheme I.

1-(2-Chloroethyl)-2-methyl-5-nitroimidazole is reacted with a cyclic thiol or the tautomeric, pseudothiourea, form of substituted thioureas to form 2-(2-methyl-5-nitro-1-imidazolyl)ethyl-2-pseudothioureas in organic polar solvents. Alcohols, dimethylsulfoxide, and dimethylformamide are suitable solvents. Thus, 1-methylthiourea and 1-(2-chloroethyl)-2-methyl-5-nitroimidazole are heated in 2-propanol for 72 hours to provide 1-methyl-2-[2-(2-methyl-5-nitro-1-imidazolyl)ethyl]-2-thiopseudourea hydrochloride. The free base is obtained by neutralization of the hydrochloride in aqueous base, followed by extraction of the product with ether. Thus the above mentioned hydrochloride is converted to 1-methyl-2-[2-(2-methyl-5-nitro-1-imidazolyl)ethyl]-2-thiopseudourea.

The compounds of the present invention are useful in view of their anti-microbial activity. They are especially effective in inhibiting the growth of protozoa.

Evidence of the anti-protozoal utility of the present compounds is obtained from standardized tests designed to determine the capacity of test compounds to inhibit the growth of *Trichomonas vaginalis*. These tests are carried out in the following manner. A modified Diamond medium is prepared by mixing 1200 parts of trypticase (Baltimore Biological Laboratories), 600 parts of yeast extract (Difco), 300 parts of maltose, 60 parts of L-cysteine hydrochloride, 12 parts of L-ascorbic acid, 48 parts of dibasic potassium phosphate, 48 parts of monobasic potassium phosphate and 54,000 parts of distilled water. The pH is adjusted to 6.8 with 40% sodium hydroxide solution and 30 parts of agar (Baltimore Biological Laboratories) is incorporated. The mixture is boiled for one minute to dissolve the agar and is then sterilized in an autoclave. To 80 volumes of the resultant medium is aseptically added 20 volumes of sterile Dubos medium serum. The resultant medium is inoculated with 1% by volume of a 72 hour culture of *Trichomonas vaginalis*, whereupon 1 ml. of the inoculated medium is mixed with 10 mg. of test compound. The mixture is incubated anaerobically at 37°C. for 48 hours and then examined microscopically for the presence of motile trichomonads. If any are observed, the compound is considered inactive. If no mo-

tile trichomonads are observed, 0.1 ml. of the incubated mixture is serially diluted and mixed with quantities of the inoculated medium sufficient to produce concentrations of 1000, 100, 10 and 1 micrograms of test compound per ml. and the resulting mixtures are incubated anaerobically as before at 37°C. for 48 hours and then examined microscopically for the presence of motile trichomonads. Controls are provided by concurrent incubation identical with the foregoing except for the absence of test compound.

The following examples are presented to further illustrate the present invention. They should not be construed as limiting it either in spirit or in scope. In these examples quantities are indicated in parts by weight unless parts by volume are specified, and temperatures are indicated in degrees Centigrade (°C.). The relationship between parts by weight and parts by volume is the same as that existing between grams and milliliters.

EXAMPLE 1

4.5 Parts of 1-methylthiourea and 9.5 parts of 1-(2-chloroethyl)-2-methyl-5-nitroimidazole are dissolved in 50 parts by volume of 2-propanol and heated for 72 hours. The solution is cooled and diluted with 25 parts by volume of acetone and 25 parts by volume of ether, resulting in crystallization of 1-methyl-2-[2-(2-methyl-5-nitro-1-imidazolyl)ethyl]-2-thiopseudourea hydrochloride, melting at 205°-206.5°. The formula of this compound is

Neutralization with base and extraction with ether provides 1-methyl-2-[2-(2-methyl-5-nitro-1-imidazolyl)ethyl]-2-thiopseudourea.

EXAMPLE 2

5.2 Parts of 1,3-dimethylthiourea and 9.5 parts of 1-(2-chloroethyl)-2-methyl-5-nitroimidazole are dissolved in 50 parts by volume of 2-propanol and heated for 72 hours. The solution is cooled and diluted with 25 parts by volume of acetone and 25 parts by volume of ether, thus effecting crystallization of 1,3-dimethyl-2-[2-(2-methyl-5-nitro-1-imidazolyl)ethyl]-2-thiopseudourea hydrochloride, melting at 202°-205°. The formula of this compound is

Neutralization with base and extraction with ether provides 1,3-dimethyl-2-[2-(2-methyl-5-nitro-1-imidazolyl)ethyl]-2-thiopseudourea.

EXAMPLE 3

3.8 Parts of thiourea and 9.5 parts of 1-(2-chloroethyl)-2-methyl-5-nitroimidazole are dissolved in 50 parts by volume of 2-propanol and heated for 84 hours, then are cooled. 2-[2-(2-Methyl-5-nitro-1-imidazolyl)ethyl]-2-thiopseudourea hydrochloride separates as a solid, melting at 234°-236°. The formula of this compound is

10

20 Neutralization with base and extraction with ether provides 2-[2-(2-methyl-5-nitro-1-imidazolyl)ethyl]-2-thiopseudourea.

EXAMPLE 4

25 66 Parts of 1,3-diethylthiourea and 9.5 parts of 1-(2-chloroethyl)-2-methyl-5-nitroimidazole are dissolved in 50 parts by volume of 2-propanol and heated for 72 hours. The solution is cooled and diluted with 25 parts by volume of acetone and 25 parts by volume of ether, resulting in crystallization of 1,3-diethyl-2-[2-(2-methyl-5-nitro-1-imidazolyl)ethyl]-2-thiopseudourea hydrochloride. The formula of this compound is

35

Neutralization with base and extraction with ether provides 1,3-diethyl-2-[2-(2-methyl-5-nitro-1-imidazolyl)ethyl]-2-thiopseudourea.

45

50

EXAMPLE 5

1.2 Parts of 1,4,5,6-tetrahydropyrimidine-2-thiol and 1.8 parts of 1-(2-chloroethyl)-2-methyl-5-nitroimidazole are dissolved in 30 parts by volume of 2-propanol and 10 parts by volume of methanol. The resulting solution is heated for 24 hours and cooled. The solid which forms is crystallized from acetone. This procedure provides 2-[2-(2-methyl-5-nitro-1-imidazolyl)ethylthio]-1,4,5,6-tetrahydropyrimidine hydrochloride, melting at 208°-211°. The formula of this compound is

55

60

Neutralization with base and extraction with ether provides 2-[2-(2-methyl-5-nitro-1-imidazoly)ethylthio]-1,4,5,6-tetrahydropyrimidine.

EXAMPLE 6

8.6 Parts of 1-butyl-1,4,5,6-tetrahydropyrimidine-2-thiol and 9.5 parts of 1-(2-chloroethyl)-2-methyl-5-nitroimidazole are dissolved in 50 parts by volume of 2-propanol and heated for 72 hours. The solution is cooled and diluted with 25 parts by volume by acetone and 25 parts by volume of ether. The resulting solid is 1-butyl-2-[2-(2-methyl-5-nitro-1-imidazoly)ethylthio]-1,4,5,6-tetrahydropyrimidine hydrochloride, melting at 130°-131°. The formula of this compound is

Neutralization with base and extraction with ether provides 1-butyl-2-[2-(2-methyl-5-nitro-1-imidazoly)ethylthio]-1,4,5,6-tetrahydropyrimidine.

EXAMPLE 7

3.3 Parts of 1-methyl-1,4,5,6-tetrahydropyrimidine-2-thiol and 5.7 parts of 1-(2-chloroethyl)-2-methyl-5-nitroimidazole are dissolved in 25 parts by volume of 2-propanol and heated for 24 hours. The solution is cooled and diluted with 10 parts by volume of acetone and 10 parts by volume of ether. The resulting solid is 1-methyl-2-[2-(2-methyl-5-nitro-1-imidazoly)ethylthio]-1,4,5,6-tetrahydropyrimidine hydrochloride, melting at 186°-188°. The formula of this compound is

Neutralization with base and extraction with ether provides 1-methyl-2-[2-(2-methyl-5-nitro-1-imidazoly)ethylthio]-1,4,5,6-tetrahydropyrimidine.

EXAMPLE 8

3.2 Parts of 2-mercaptop-1-methylimidazole and 5.7 parts of 1-(2-chloroethyl)-2-methyl-5-nitroimidazole are dissolved in 25 parts by volume of 2-propanol and heated for 24 hours. The solution is cooled and diluted with 10 parts by volume of acetone and 10 parts by volume of ether. The resulting solid is 1-methyl-2-[2-(2-methyl-5-nitro-1-imidazoly)ethylthio]imidazole hy-

drochloride, melting at 201°-202.5°. The formula of this compound is

Neutralization with base and extraction with ether provides 1-methyl-2-[2-(2-methyl-5-nitro-1-imidazoly)ethylthio]imidazole.

EXAMPLE 9

1-Methyl-2-[2-(2-methyl-5-nitro-1-imidazoly)ethylthio] imidazole hydrochloride, 9.6 parts is dissolved in 100 parts of water and neutralized with 1.3 parts of sodium hydroxide. The free base separates as a solid, melting at 112.5°-114°. It is mixed with 25 parts by volume of concentrated nitric acid and 10 parts of water and heated to 90° for an hour. The solution is diluted with 460 parts of water and partly neutralized with sodium carbonate. The solid which forms is separated by filtration and triturated with methanol to yield 1-methyl-2-[2-(2-methyl-5-nitro-1-imidazoly)ethylthio]-5-nitroimidazole, melting at 209°-214°. The formula of this compound is

Treatment with hydrochloric acid provides 1-methyl-2-[2-(2-methyl-5-nitro-1-imidazoly)ethylthio]-5-nitroimidazole hydrochloride.

What is claimed is:

1. A compound of the formula

wherein R₃ is hydrogen or lower alkyl containing 1-7 carbon atoms and R₁ and R₂ are hydrogen, lower alkyl containing 1-7 carbon atoms, or R₁ and R₂ together are vinylene, nitrovinylene, or trimethylene or the pharmaceutically acceptable acid addition salts thereof.

2. A compound of claim 1 wherein R₁ and R₂ are hydrogen or lower alkyl.

3. The compound of claim 2 which is 1-methyl-2-[2-(2-methyl-5-nitro-1-imidazoly)ethyl]-2-thiopseudourea.

4. The compound of claim 2 which is 1-methyl-2-[2-(2-methyl-5-nitro-1-imidazolyl)ethyl]-2-thiopseudourea hydrochloride.

5. The compound of claim 2 which is 1,3-dimethyl-2-[2-(2-methyl-5-nitro-1-imidazolyl)ethyl]-2-thiopseudourea.

6. The compound of claim 2 which is 1,3-dimethyl-2-[2-(2-methyl-5-nitro-1-imidazolyl)ethyl]-2-thiopseudourea hydrochloride.

7. The compound of claim 2 which is 2-[2-(2-methyl-5-nitro-1-imidazolyl)ethyl]-2-thiopseudourea. 10

8. The compound of claim 2 which is 2-[2-(2-methyl-5-nitro-1-imidazolyl)ethyl]-2-thiopseudourea hydrochloride.

9. A compound of claim 1 wherein R1 and R2 together are trimethylene.

10. The compound of claim 9 which is 2-[2-(2-methyl-5-nitro-1-imidazolyl)ethylthio]-1,4,5,6-tetrahydropyrimidine.

11. The compound of claim 9 which is 2-[2-(2-methyl-5-nitro-1-imidazolyl)ethylthio]-1,4,5,6- 20

tetrahydropyrimidine hydrochloride.

12. The compound of claim 9 which is 1-butyl-2-[2-(2-methyl-5-nitro-1-imidazolyl)ethylthio]-1,4,5,6-tetrahydropyrimidine.

13. The compound of claim 9 which is 1-butyl-2-[2-(2-methyl-5-nitro-1-imidazolyl)ethylthio]-1,4,5,6-tetrahydropyrimidine hydrochloride.

14. A compound of claim 1 wherein R1 and R2 together are vinyl or nitrovinyl.

15. The compound of claim 14 which is 1-methyl-2-[2-(2-methyl-5-nitro-1-imidazolyl)ethylthio]-5-nitroimidazole.

16. The compound of claim 14 which is 1-methyl-2-[2-(2-methyl-5-nitro-1-imidazolyl)ethylthio]-5-nitroimidazole hydrochloride.

17. The compound of claim 14 which is 1-methyl-2-[2-(2-methyl-5-nitro-1-imidazolyl)ethylthio]imidazole.

18. The compound of claim 14 which is 1-methyl-2-[2-(2-methyl-5-nitro-1-imidazolyl)ethylthio]imidazole hydrochloride.
